CLAIM

The ornamental design for an overshoe, as shown and described.

DESCRIPTION

FIG. 1 is a front left isometric view of the overshoe of the present invention;

FIG. 2 is an isometric bottom view thereof;

FIG. 3 is an isometric view of one tread member thereof;

FIG. 4 is a left side view thereof;

FIG. 5 is a right side view thereof;

FIG. 6 is a top view thereof;

FIG. 7 is a bottom view thereof;

FIG. 8 is a front view thereof;

FIG. 9 is a rear view thereof; and,

FIG. 10 is an environmental view, illustrating the overshoe of the invention in cooperation with an inner shoe.

The portions of the overshoe shown in broken lines form no part of the claimed subject matter.
